METHOD OF FORMING COMPLEMENTARY CONCRETE DIES

James Hugh Brown, Seattle, Wash.

Application May 1, 1942, Serial No. 441,415

4 Claims. (Cl. 25—155)

My invention relates to the shaping and contouring of laminated wood, ply wood or veneer, and the molding of plastic materials, and has among its objects and advantages the provision of an improved mold and a method of making the same.

Considerable difficulty has been experienced in the construction of iron and steel molds in the nature of a shoe and a die for bending and shaping structural materials, particularly in cases where the shapes are in the nature of bends or geometrical curves in both single and compound curvatures. In the case of iron or steel, each mold part has to be separately cast from a separate pattern. This method does not insure, in the molding of each part, a perfect conformity and contour. Such methods require much expensive machine work on both the die and the shoe in order that they shall closely conform to and contour with each other. Then, too, there is the further problem of warping and shrinking peculiar to metallic shoes and dies.

Accordingly, an object of my invention is to provide a novel shoe and die combination wherein the two parts may be accurately shaped to closely conform to and contour one with the other, and in which the parts are constructed of material which entirely eliminates objectionable warpage and shrinkage.

A further object is to provide a mold comprising coacting die and shoe units formed of concrete or other initially plastic material wherein the shoe and the die are provided with internal and external reinforcing means, and in which the die and the shoe are provided with means for circulating a heating and drying or cooling medium therethrough for subjecting the work being bent or shaped to the required temperature conditions.

A further object is to devise a novel method of forming a mold comprising a shoe and a die having coating surfaces for shaping and bending construction materials, which method comprises the formation of one unit of the mold with a face having a predetermined contour and then hardening the unit, after which the other unit is formed by the application of an initially plastic material to the contour face of the previous unit so as to secure an accurately shaped coating face on the second unit, together with the use of a thin separator between the two units to facilitate separation thereof upon hardening of the second unit.

Another object is to provide a novel mold wherein a flexible pressure or suction responsive

means may be employed in connection with a rigid mold member to bend or shape construction materials to the contour of the rigid mold member.

55 member; and

Figure 17 is a view of a holder for the members of Figures 15 and 16.

In the embodiment selected for illustration, I make use of a concrete shoe 10 and a concrete die 12. The shoe 10 is provided with a shaping and bending face 14 and the die 12 is provided with a correspondingly shaped face 16. Figure 1 illustrates sheets 18 of ply wood arranged between the faces 14 and 16 to be bent to the contour of the faces and united into a unitary structure by grooved joints between the respective ply wood sheets. A sheet 20 of pliable material, such as rubber, is positioned between the face 14 and the lowermost ply wood sheet 18. A similar pliable sheet 22 is placed between the face 16 and the uppermost ply wood sheet 18. The sheets 20 and 22 are employed only in such cases as where the materials being fabricated are characterized by slight or pronounced irregularities which prevent effective pressure from being applied throughout the entire area of the assembly. In most cases the pliable sheets may be dispensed with and the structural materials arranged for direct engagement with the two forming faces 14 and 16.

After application of glue to the engaging faces of the sheets 18, pressure is brought to bear on the assembly through tightening of nuts 24 on rods 26 passing through openings in lugs 28 partially embedded in the concrete of the respective shoe and die 10 and 12. This pressure condition serves as a holding means until such time as the required pressure is applied by means of hydraulic or other external means of like force and strength. The assembled sheets are maintained under pressure until the glue has dried thoroughly. When the glue has been properly dried, the sheets 18 are secured firmly one to the other and the assembly has a contour conforming to the faces 14 and 16.

In order to position and retain the die 12 in true vertical relationship with the shoe 10, guide rods 30 are slipped through eyes 32 in both the shoe and the die, which rods are preferably hooked at 34 to engage the upper face of the die 12 to be restrained from downward longitudinal movement. The eyes 32 are also partly embedded in the concrete of the shoe and the die.

In securing the sheets 18 into a unitary structure by means of glue, the glue frequently acts as a lubricant which causes the sheets to shift laterally when pressure is applied to the assembly. In cases where it is desirable to restrain the sheets from such relative lateral displacement, aligning bars 36 are brought into engagement with the edges of the sheets 18, which bars are secured to shafts 38 supported in eyes 40 on sleeves 42 slidably mounted on rods 44 held in eyes 46 anchored in the concrete of the shoe and the die. The shafts 38 are movable longitudinally in the eyes 40 and may be secured in different positions by set screws 48. Sets of bars 36 of different lengths may be provided for use in bending and shaping materials of different total thicknesses.

In cases where it is desirable to arrange the edges of the sheets 18 in offset relationship, spacing fingers 50, see Figure 6, may be employed. Each group of fingers 50 is carried by a bar 52 corresponding to one of the bars 36, and the bars 50 are adjustable horizontally and vertically through the medium of bolts 54 which pass through a slot 56 in the bar 52 and through slots 58 in the respective fingers. The bars 52 may be substituted for the bars 36 in the eyes 40.

The offset arrangement of the sheets 18 in Figure 6 provides an edge contour wherein the respective sheets of one assembly may be joined in overlapping relationship with the sheets in another such assembly to provide a strong joint.

Frequently it is desirable to heat the shoe and the die for work drying purposes. Figures 1 and 4 illustrate the shoe and the die as being provided with steam pipes 60 embedded in the material of the respective bodies. One or more such pipes may be embedded in each unit, as the particular situation may demand or require, with the pipes bent to zigzag contour, and with the ends of the pipes projecting sufficiently far from the units to provide connections for steam conduits. A cooling medium may be circulated through the pipes if a low temperature condition is desired. To facilitate handling of the shoe and the die, each is provided with two pipes 62 embedded therein and extending the full width thereof so that lifting rods may be inserted in the pipes for connection with a lifting hoist. The lifting rods are indicated at 64 in dotted lines in Figure 4.

Figure 1b illustrates a box or form 66 which may be placed on a floor or table 68. The upper faces 70 of the side walls 72 are contoured to produce the curvature, single or compound, desired. The concrete is poured into the box 66 and the face of the shoe shaped to the desired contour, with the faces 70 acting as a guide or aid in shaping the shoe face. When the shoe is solidified, the box 66 is removed from the shoe by unloosening the tie rods 74. The tie rods are again tightened after the removal of the box from the shoe, and the box is reversed and placed directly over the shoe, with a sheet of oiled paper on the face of the shoe as a separating means. Concrete is then poured into the box to produce a die having a contour conforming exactly to the face of the shoe, since the shoe then constitutes the bottom of the box.

Figures 2 and 3 illustrate a shoe 76 and a die 78 of the same contours as the shoe 10 and the die 12. In the construction of Figures 2 and 3, both the shoe and the die are provided with a plurality of parallel reinforcing members 80 in the nature of I beams embedded in the concrete of the respective bodies. Additional reinforcing rods 82 are also embedded in the shoe and the die in right angular relationship with the I beams 80.

The shoe 76 and the die 78 are provided with means to resist chipping and cracking of the concrete about the respective bending and shaping faces 84 and 86, respectively. This reinforcement comprises steel frames 88 engaging the four faces 90 on the respective shoe and die bodies. The frames 88 terminate slightly short of the respective faces 84 and 86, and each frame 88 includes a narrow flange 92 lying in engagement with the rear face of its respective concrete body. Key flanges 94 are formed on each of the frames 88 to be embedded in the concrete for firmly anchoring the frame. The lugs 96 corresponding to the lugs 28 are carried by the frames 88.

Both the shoe and the die of Figures 2 and 3 are provided with steam pipes 98. The frames are also provided with eyes 100 corresponding to the eyes 32 and 46 for supporting aligning rods 102 and guide rods 104 of the type illustrated at 30 and 44, respectively, in Figure 1. Lift pipes 106 are also embedded in the concrete of the shoe and the die.

Figure 7 illustrates a concrete shoe 108 lying

in a steel pan 110 provided with a flange 112 about its open end. Enclosing the upper portion of the shoe 108 is a flexible or rubber cap 114 secured between the flanges 112 and bars 116 by bolts 118. The work to be shaped is indicated at 120 as lying on the contour face 122 of the shoe 108 and inside the cap 114. A pipe 124 is attached to the cap 114 and has communication with the space between the cap and the shoe. This pipe is connected with a vacuum pump (not shown) for bringing the cap 114 into pressure engagement with the work to bend it to the contour face 122 through evacuation of the air in the work space.

Figure 8 illustrates a shoe 126 having lugs 128 partly embedded in the material of the shoe for anchoring purposes. To the lugs 128 is detachably connected a steel cap 130 by bolts 132. The work 134 is located between the contour face 136 of the shoe and a flexible bag or envelope 138 lying inside the cap 130. A pipe 140 extends through the cap 130 and has communication with the bag 138 for admitting air under pressure to bend the work to the contour face 136. The cap 130 provides an enclosure for the bag 138 so that expansion thereof confines its inflation in a work direction to effectively contour the work to the face 136.

Figure 9 illustrates means for shaping a shoe having such extreme contours as to necessitate the formation of a pattern to mold the face of the shoe. In the form 142 is placed a pattern 144 having a shoe-shaping face 146 characterized by sharp curves 148. The face 146 is treated with wax, grease or the like and the concrete is poured into the form and over the pattern 144, which gives the concrete body facial characteristics conforming to the face 146. After the concrete has set, the body and the pattern are removed from the form and the body is reversed and replaced in the form with its contoured face facing up. Oiled paper or the like is then applied to the contoured face of the body and concrete is again poured into the form to shape the die in conformity with the facial characteristics of the shoe.

Figure 10 illustrates a shoe or die body 150 having a steel jacket 152 extending about its side edges and face 154 opposite the contour face 156. Reinforcing ribs 158 are formed on the inner faces of the jacket 152 for strengthening the body 150.

In Figure 11, a series of shoes 160 and a series of dies 162 are arranged in abutting relationship upon a common base 164 for shaping a relatively large piece of work 166. The shoes and dies may be identical with those of Figure 1 with respect to clamps, aligning means, guides and heating or cooling means, with the exception that these devices should be so arranged as to permit end to end engagement between the respective shoe and die elements in the series, thereby providing continuous pressure faces.

The mold of Figure 12 comprises a shoe 168 having a face contour 170 and a die 172 having a face contour 174 coacting with the face 170 to bend plywood 176 or the like for the construction of tank walls and similar structures. The face 174 is characterized by a smaller diameter than the face 170 so as to provide uniform spacing between the two faces. In the form of Figure 12 the two faces 170 and 174 are independently shaped to size and contour, since one face can not be shaped by pouring concrete over

the other face because of the difference in diameters of the respective faces. Both the die and the shoe may be provided with conduits for a heating or cooling medium, as well as the clamps, guides and the aligning means of Figure 1.

Figures 13 through 16 illustrate a further modification in the work guiding means. Figure 13 illustrates a plurality of sheets 176 arranged in overlapping relationship between the shoe section 178 and the die section 180, as when being glued or cemented into a unitary structure. To the shoe section 178 are connected two gage brackets 182, which brackets are located on opposite faces of the shoe and secured thereto by bolts 184 embedded in the material of the shoe. Two similar gage brackets 188 are attached to the die 180 by bolts 186. The brackets 186 are located vertically above the brackets 182. Each bracket is provided with two bores 190, the bores in the brackets 182 being respectively co-axially arranged with the bores in the brackets 186. Gage guide rods 192 are slipped through the aligned bores 190 and preferably made secure to the brackets 182 by set screws 194.

A gage holding body 196 is mounted upon each set of rods 192. Bores 198 are provided in the bodies 196 for loosely receiving the rods 192.

Each of the bodies 196 is provided with a transverse rectangularly-shaped opening 200. A tongue-forming guide 202 is inserted in the slot 200 in one body 196 and made secure by a set screw 204. This guide is provided with shoulders 206 so spaced and arranged as to about the sheets 176 in the laterally offset relationship of Figure 13 to provide a tongue formation 208. Guide 200 extends to a position between the shoe 178 and the die 180 and its vertical dimension is narrower than the spacing between the shoe and the die to provide clearance in the closest spacing of the shoe and the die.

A work guide 210 is inserted in the other body 196 and may be made secure by a set screw 212. This work guide is provided with shoulders 214 so arranged as to engage the opposite edges of the sheets 176 when the latter are relatively laterally offset in the manner of Figure 13 and in conformity with the work guide 202. The work guide 210 is also narrower than the closest spacing between the shoe and the die, and either work guide 202 or 210 may be adjusted to bring the edges of the sheets 176 into desired holding engagement with the respective shoulders 206 and 214 to restrain the sheets 176 from relative lateral shifting when pressure is applied to the assembly. While the set screws 194 firmly secure the rods 192 against vertical movement, the brackets 186 are free to move longitudinally on the rods 192, as when the die 180 is moved vertically relatively to the shoe 178. When the sheets 176 have been thoroughly secured into a unitary assembly, the assembly is characterized by a tongue 208 along one edge and a groove formation 216 along its opposite edge for receiving the tongue formation 208 on another assembly. Thus sections of assemblies may be effectively joined one to the other and with the respective sheets of the assemblies overlapping one with the other.

While I have employed specific designs to illustrate the purpose, scope and function of my invention, I am not to be restricted to these, provided always, of course, that I confine such other designs as I may employ within the scope and principle of my invention.

Without further elaboration, the foregoing will so fully illustrate my invention, that others may,

by applying current knowledge, readily adapt the same for use under various conditions of service.

I claim:

1. The method of forming a shaping mold comprising a concrete shoe in the nature of a monolith and having sides and ends, and a top and bottom face, the whole of the top face constituting a work-shaping face and a concrete die in the nature of a monolith and having sides and ends, and a top and bottom, the whole of the bottom face of which constituting a work-shaping face which consists in preparing a form having an edge contour conforming to the predetermined perimetrical contour of the work-shaping face of the shoe, pouring concrete into said form and shaping the face of the concrete to said edge contour and the predetermined face contour of the shoe and allowing the concrete to set, removing the form from the hardened shoe, applying a separator medium upon the work-shaping face of the shoe, arranging the form upon the shoe, pouring concrete into the form to form the die with a work-shaping face the whole of which contoured from the work-shaping face of the shoe, allowing the die to harden, and subsequently separating the die from the shoe at their juncture with said separator medium.

2. The method of forming a shaping mold comprising a monolithic-like concrete shoe the whole of one face being a work-shaping face and a monolithic-like concrete die the whole end of one face having an identical work-shaping face which consists in pouring the shoe as a unit, forming the work-shaping face on the shoe and allowing the concrete to set, applying a separator medium to the work-shaping face of the shoe, and subsequently pouring the concrete of the die as a unit upon the work-shaping face of the shoe and allowing the concrete to set, and subse-

quently separating the die from the shoe at their juncture with said separator medium.

3. The method of forming a shaping mold comprising a concrete shoe in the nature of a monolith having a work-shaping face and a concrete die in the nature of a monolith having an identical work-shaping face which comprises forming a pattern contoured to the work-shaping face of the shoe, applying a separating medium on the pattern, placing the pattern in a form and pouring the concrete upon the pattern to contour the work-shaping face of the shoe, allowing the concrete to set, removing the shoe from the pattern and applying a separator medium to the work-shaping face of the shoe, pouring the concrete of the die upon the work-shaping face of the shoe to shape the work-shaping face of the die in conformity with the work-shaping face of the shoe, allowing the concrete of the die to set, and subsequently separating the die from the shoe at their juncture with said separator medium.

4. The method of forming complementary shoe and die sections each having a monolithic character of a plastic shaping mold having co-acting work-shaping faces which comprises molding one section as a unit in a form having the top edges conforming to the edge contour of a selected work-shaping face, placing a separator medium on the uppermost work-shaping face of the section, removing the said form from the molded section, and mounting said form in reversed position for molding the complementary section as a unit on the first section and the separator thereon so that the lowermost work-shaping face of the upper section will accurately conform to the work-shaping face of the bottom section.

JAMES HUGH BROWN.
